PLASTIC FRAME CONSTRUCTION
 Robert C. Wagner, R.R. 4, Bellevue, Ohio
 Filed May 9, 1961, Ser. No. 103,871
 2 Claims. (Cl. 20—16)

This invention relates to frames, such as door and window frames and sashes, and particularly to a frame which is fabricated from extrusions of set synthetic organic plastic.

The principal object of the invention is to provide a frame of this character which is precisely shaped and which is reinforced in a manner such that whipping and bowing of the frame out of its normal plane are greatly reduced.

For the purposes of illustration, the invention is described as applied to a vinyl frame for screen or glass pane doors, its application to other types of plastic and frames being readily apparent from the illustrative example.

Heretofore, in the formation of vinyl door frames, attempts have been made to obtain sufficient rigidity to prevent the frame from warping, bulging, or bowing out of its normal plane and to eliminate the so-called "whip," by increasing the wall thickness. The whip is particularly objectionable because it prevents the doors from seating properly in the door jamb and also results in the breaking of the glass panes.

When such doors are closed with obstructing foreign objects between the door frames and jambs, the doors flex. If a door is held by the latch in flexed condition for a predetermined period, it warps permanently in the flexed shape.

These frames almost always are fabricated from rails cut from plastic extrusions which are hollow or tubular so as to provide maximum rigidity with as thin walls as possible, thus reducing the amount of the relatively expensive plastic required.

To increase the vertical rigidity and reduce bowing, metal reinforcing tubes or channels of aluminum or steel have been inserted inside the hollow or tubular extruded rails, and gussets have been used to reinforce the frames at the corners. This type of construction is very expensive due to complex fabricating steps required and inconsistent results obtained. To eliminate this difficulty, an attempt was made to weld or fuse the reinforcing members and gussets together at the corners, and while a fairly rigid door could be obtained by this method, some whip remained and introduced sales objections, and the welding operation was very expensive.

Another approach was to eliminate the use of the metal reinforcing tubes or bars inside of the sections and, instead, to extrude webs or ribs for imparting rigidity. This approach, however, required multi-port dies and presented difficult extrusion problems which eventually led to its rejection. For example, the addition of webs and ribs did not yield sufficiently increased strength to prevent bowing of the door, and they caused deformities in the face of the extrusion at their junctures therewith. These deformities adversely affected the appearance and market desirability. Again, consistent tolerances could not be obtained on successive extrusion runs.

In accordance with the present invention, the frame of extruded plastic is so arranged that a simple hollow or tubular extruded section of aluminum or like material can be secured thereto easily and cooperate therewith to reinforce the frame adequately and thereby reduce warping and whipping to an unobjectionable amount.

Various other objects and advantages will become apparent from the following description wherein reference is made of the drawings, in which:

FIG. 1 illustrates a front elevation of a door frame embodying the principles of the present invention;

2

FIG. 2 is an enlarged fragmentary view of the upper right-hand corner of the frame illustrated in FIG. 1, partly in section, showing the arrangement of the frame rails and the connection of the reinforcing members; and

FIGS. 3 and 4 are enlarged cross sectional views taken on the lines 3—3 and 4—4, respectively, in FIG. 1.

Referring to the drawings, the door frame comprises essentially a pair of spaced side rails or frame members 1 with cross end rails or frame members 2 connected to the ends thereof. If desired, a suitable cross rail or frame member 3 may be provided intermediate the ends of the side frame members 1. The side frame members 1 and the end frame members 2 are lengths cut from identical extrusions of vinyl or suitable set plastic, such as high impact plastic. Each comprises a hollow tubular portion 5 having an outer decorative side wall 6 and an inner side wall 7, joined by an outer peripheral wall 8 and inner peripheral wall 9. The wall 9 has a flange 10 extending inwardly of the frame parallel to the walls 6 and 7 and offset from the planes thereof so as to act as a stop for a framed screen or pane installed in the opening defined by the wall 8. The frame members are tubular and, when assembled, the outer wall 8 is exposed outwardly of the finished door edgewise of the door. The assembled frame has mitered corners, the frame members being bonded together at the corners by fusion of the plastic material at the juncture, either by heat or plasticizers. Thus the vinyl frame becomes a unitary structure.

The side walls 6 and 7 have integral flanges 11 which, together with the wall 8, define an outwardly open peripheral channel 12. The flanges 11 are formed with shoulders or abutments 13 which protrude inwardly from the flanges and restrict the side of the channel 12. As a result, the channel 12 can receive and snugly accommodate a tubular reinforcing member, such as indicated at 14.

The tubular member 14 preferably is one having an outboard wall 15 and an inboard wall 16 joined by walls 17. The inboard face of the inboard wall 16 is arranged so that, when the member 14 is installed in the channel 12, it fits snugly against the outboard face of the wall 8, and the outboard face of the wall 15 is engaged along its margins by the inner faces of the abutments 13 and thus held securely in the channel. The walls 17 of the member 14 preferably are juxtaposed in face to face relation with the inner faces of the flanges 10 and 11. If desired, the member 14 may be cemented in place, thus increasing the rigidity of the frame.

The member 14 is a tubular extrusion, preferably of aluminum or like metal, and preferably is reinforced internally. On its inner wall 16, it is provided with integral channels 18 which are so configured as to reinforce the inner wall 16. The open sides of the channels 18 are restricted so that the channels provide longitudinal open sided passages 19. These passages are adapted to receive screws, as indicated at 20, in coaxial relation therewith for securing the reinforcing members 14 together to form a mitered corner. By the use of self-threading screws, the members 14 can be drawn tightly together at the corners of the frame. The passages 19 extend longitudinally of the members 14 and are preferably coextensive with the length thereof.

When the members 14 are assembled together, as illustrated in FIG. 2, they completely embrace the frame, each side frame member 1 and top frame member 2 being provided with a reinforcing member 14 coextensive in length therewith. The screws 20 are introduced through the reinforcing members of the side frame members by boring suitable horizontal holes therethrough in alignment with the passages 19 in the channels 18. The screws 20 are then passed therethrough and threadably engage the walls of the channels 18 by cutting their own threads

therein. They draw the members 14 of the side frame members 1 and of the top and bottom frame members 2 fixedly together in position, so that they tightly embrace the peripheral edge of the frame. Thus, no welding is required and a rigid reinforced door structure is provided without increasing the thickness of the walls of the plastic extrusion and without internal webbing and the like. If facilities for welding are available, the members 14 may be connected together by welding, which, since the members are all readily accessible exteriorly of the frame, does not interpose impractical procedures.

The cross frame members 3 may be formed of plastic, but provided with channels 21 corresponding to the channels 18. Thus by passing screws 22 through the side frame members 1 and their associated members 14, into the channels 21, the cross frame members can be fixedly secured in place.

With this arrangement, the door frame is reinforced and is made sufficiently rigid without an increase in the thickness of the walls of the plastic material and without expensive webbing. Likewise, the combination can be effected without welding internal reinforcing members and without specialized equipment, by the insertion of ordinary self-threading screws.

However, if welding of the reinforcing members is desired, such can be effected more readily as the reinforcing members are exposed exteriorly of the frame. Thus a frame of extrusions of vinyl or synthetic organic plastic material is provided which has mitered fused corners and reinforcing members which are readily fastened together after the frame is otherwise complete.

In those instances where the corners formed by the bonded plastic are sufficiently strong so that the only whip to be eliminated is due to the flexure of the plastic members intermediate the joints, the reinforcing members may be left unconnected at the corners, or terminate short of the corners. In such cases, the reinforcing members are secured to the frame only by cementing them in the channels of the frame.

Having thus described my invention, I claim:

1. A frame structure comprising a unitary main frame, complete in and of itself, of extruded tubular side, top, and bottom frame members of identical cross section throughout their lengths and of set organic plastic material having mitered joints fusion bonded together in fixed position relative to each other at the corners, respectively, of the frame, each of said main frame members having at

5 its outer edge a pair of integral flanges in spaced face to face relation to each other and extending lengthwise of said outer edge the full length thereof and defining with said outer edge a channel which opens outwardly edgewise of the main frame, the channels of said members defining a continuous channel extending completely about the outer peripheral edge of the main frame and opening outwardly edgewise of the main frame, a reinforcing frame complete in and of itself of stiff metal side, top, and bottom reinforcing members, respectively, said reinforcing frame being disposed in said channel and juxtaposed against the edges of the main frame therebetween and filling the space between the flanges and having mitered joints at the corners, respectively, the corners of the reinforcing frame being disposed for access exteriorly of the main frame for connection of the reinforcing members together at the corners in firm embracing relation to the main frame, connecting means at the corners of the reinforcing frame, respectively, each of said connecting means including at least one screw assembly, at its associated corner, for operation from the exterior of the reinforcing frame, each connecting means securing its associated reinforcing members together at the associated mitered corner of the reinforcing frame independently of the main frame and holding the mitered surfaces of the associated reinforcing members in firm stressed juxtaposition with each other under pressure applied by the screw.

2. The structure according to claim 1 wherein each screw extends through one of the reinforcing members, edgewise thereof from the outer edge of the reinforcing frame with its head at the outer edge, and is slidable axially thereacross and has a threaded inner end portion extending endwise of the other reinforcing member at the associated corner and in threaded engagement therewith, so that upon rotation of the screw said mitered edges of the associated reinforcing member can be drawn thereby into said stressed relation.
